United States Patent Office.

J. NELSON JACOBS, OF WORCESTER, MASSACHUSETTS.

Letters Patent No. 71,491, dated November 26, 1867.

IMPROVED KNIFE AND SCISSORS-SHARPENER.

The Schedule referred to in these Letters Patent and making part of the same.

TO ALL WHOM IT MAY CONCERN:

Be it known that I, J. NELSON JACOBS, of Worcester, in the county of Worcester, State of Massachusetts, have invented a new and improved Instrument or Tool for Sharpening Knives and Scissors; and I do hereby declare that the following is a full and exact description thereof, reference being had to the accompanying drawings, and to the letters of reference marked thereon.

Like letters refer to like parts.

The nature of my invention consists in so arranging a narrow flat float-file in a block of metal, plaster of Paris, wood, or other material, that the edge of the several teeth on the file shall form an angle of about forty-five degrees with the guard. Then, by placing the blade of the knife or scissors in proper position (which will be hereafter described) against the guard, the cutting edge of the knife or scissors will be brought into contact with the teeth of the file at such an angle as will give the proper bevel to the said cutting edge.

To enable others skilled in the art to make and use my invention, I will proceed to describe its construction and operation.

Figure 1 represents the tool arranged for sharpening both knives and scissors.

Figure 2 represents the instrument or tool arranged for sharpening scissors and shears only.

Figure 3 represents the strip or string of files as they are cut and marked off ready to be separated for use.

Figure 4 represents an edge view of the file after it is separated from the strip in which it was cut.

Figure 5 represents guard-plate used on the instrument, as shown in fig. 1—an edge view.

Like letters refer to like parts in the several figures.

A A, in figs. 1 and 2, are the blocks; E E, the slots running the length of the block (or less) for the reception of the files B B. F is the slot or opening made from the top of the block A, about the whole width, down to the lower side of the slot E, or, at least, to half the depth of the slot E. It is well to leave a little shoulder for the back edge of the file B to rest against. f f, in fig. 1, are guards for the sides of the knife to rest against, letting the edge come nearly down to the edges of the metal guard-plate C. The edges of C are bevelled to form a guide for sharpening scissors, for which purpose place the flat side of the blade against the edge 2 of the plate C, and then draw the knife or scissors from the tool, holding the tool in the left hand. D is a screw passing through the plate C into the block A, holding the plate C in its place, and the file B in its place. When the file gets worn in one place, by loosening the screw D the file may be moved along, and thus the whole length of it may be used. In fig. 2 the slot F is cut down to the bottom of the file, and across the block A, and is made wide enough to admit the thickness of the blade of large shears, and is bevelled only one way, so that the flat or inside side of the blade must be placed against the side of the slot F, marked f, bringing the cutting edge down upon the file B. Then, holding the tool in the left hand, and draw the blade towards the operator, a straight perfectly-bevelled edge will be formed on the blade of the shears. C is a round plate of metal, with a hole for screw D to pass through, which should go into the block just above the top of the file B to give it a firm hold in the block. The screw and plate hold the file in its place, and, by loosening the screw, the file can be moved along, so as to permit wearing out nearly the whole length of the file. The ends of the blocks A may be covered with a coat of emery, or other material of like nature, for the purpose of removing the wire edge formed on the inside of the blade in sharpening on the file; or they may be coated with flock, paper, leather, cloth, or other material, for the purpose of ornament or finish.

Fig. 3 shows the series of files B B B, &c., as they appear after they have been cut, marked off into widths suitable for each separate file, and hardened. The red lines show where the plate is partly cut through, so that they can be readily broken apart. Fig. 4 is an edge view of one of the files after it is broken from the strip in which it was cut.

What I claim as my invention, and desire to secure by Letters Patent, is—

1. The combination of the slots E and F, the file B, screw D, and plate C, as and for the purpose specified.
2. In combination with the above, finishing the ends of the blocks of wood by covering the same with flock, emery, or other like fine fibrous or granular substance, for the purpose specified.

J. NELSON JACOBS.
